UNITED STATES PATENT OFFICE

2,420,861

TATTING SHUTTLE

Gustav A. Carlson, Chicago, Ill., assignor to The Boye Needle Company, Chicago, Ill., a corporation of Illinois

Application May 4, 1945, Serial No. 591,954

7 Claims. (Cl. 87—58)

1

This invention relates to a tatting shuttle, and more particularly to a tatting shuttle possessing improved features which contribute to the ease and efficiency of the use of the shuttle.

An object of the invention is to provide a simple efficient tatting shuttle of improved construction. Another object is to provide a tatting shuttle having the arms thereof arranged to provide lead grooves for the thread for greater ease in winding the thread on the shuttle. Yet another object is to provide in the arms of a tatting shuttle, lead grooves at the ends thereof extending from the upper and lower sides of the arms. A further object is to provide in a tatting shuttle an integral pointed arcuate end for use in forming picots.

Other features and advantages will appear from the following specification and drawing, in which—

Fig. 1 is a side elevational view of the improved tatting shuttle; Fig. 2 is a similar side elevational view showing the thread wound on the core of the shuttle; Fig. 3 is a sectional view taken along the line 3—3 of Fig. 1; and Fig. 4 is an end elevational view taken along the line 4—4 of Fig. 1.

In the embodiment of the invention described herein, the shuttle possesses a frame 10 having a core 11 for receiving a thread winding. Preferably, the entire structure is made of a resinous material, such as a synthetic resin, although any suitable material may be used.

The core 11 for receiving the thread winding may be of any suitable size or shape and, as illustrated, consists of a flat plate having end surfaces 12 and 13 above which the thread is wound. If desired, the core 11 as shown may be provided with small holes 14 and 15 which may be used to anchor the end of the thread. Thus, the thread may be passed successively through the two holes and the end tied to the body of the thread to provide a loop.

A pair of integral arms 16 and 17 extend forwardly from opposite ends of the core 11 in opposed adjacent relation. These arms extend toward each other so as to provide at their ends relatively narrow dimensions so that the shuttle may be readily passed through the loop of thread held on the fingers in the tatting operation.

Another pair of arms 18 and 19 extend rearwardly from opposite ends of the core in opposed adjacent relation. The arms 18 and 19 are similar to the arms 16 and 17 except that the arm 19 is provided with an elongated arcuate pointed

2

end 20 which extends beyond the end of the opposing arm 18.

The pointed end 20 is used in drawing a thread through a picot, the end being passed into the picot to engage the thread, and then being withdrawn to carry the thread with it through the picot.

The inner surfaces 21 and 22 of each of the forwardly-extending arms 16 and 17 extend rearwardly from the end of the arm toward the core and are each inclined toward the adjacent opposed surface of the other arm, thus providing a tapered thread-receiving groove of a maximum width at the ends of the arms. As illustrated, the groove is substantially V-shaped and provides a lead for the thread when it is being wound on the shuttle. Similarly, the inner surfaces 23 and 24 of the rearwardly-extending arms 18 and 19 are each inclined toward the opposed adjacent surface of the other arm to provide a similar groove at this end of the shuttle.

The arms 16, 17, 18 and 19 may also be provided with inclined rounded or beveled surfaces at their upper and lower sides to provide thread-receiving grooves at these portions of the ends of the arms. As seen particularly in Fig. 3, the inner surface of the arm 16 may be inclined from its upper edge 25 downwardly and toward the arm 17. The surface may be rounded as shown at 26. Similarly, the inner surface of the arm 17 may be inclined from its upper edge 27 downwardly and toward the arm 16, as shown at 28. The same surface of the arm 17 may be inclined from its lower edge 29 upwardly and toward the arm 16, as seen at 30. Similarly, the inner surface of the arm 16 may be inclined from its lower edge 31 upwardly and toward the arm 17, as seen at 32. In this way, thread-receiving grooves having a maximum width at the upper and lower edges of the arms are provided for leading the thread when the thread is to be wound on the core. Similar grooves may be provided by the arms 18 and 19, as seen in Fig. 4, the arm 19 being provided with the inclined surfaces 33 and 34 and the arm 18 being provided with the inclined surfaces 35 and 36.

As illustrated the core of the shuttle is substantially rectangular at the horizontal plane and has substantially flat upper and lower surfaces only slightly spaced apart to provide a relatively thin core body. Each pair of arms forms a continuation of the core. Each of the arms is also thick in substantially the same plane as the core and is provided with substantially flat upper and lower surfaces.

In use, the thread is secured to the core 11 by passing it through the holes 14 and 15 and forming a loop through these holes, and is then wound about the core to provide a threaded shuttle, as seen in Fig. 2. In the winding of the thread about the core, the thread is passed between the adjacent arms 16 and 17 and between the adjacent arms 18 and 19. The thread engages the substantially V-shaped grooves formed at the ends of each pair of arms and also at the upper and lower sides of each of the pair of arms. In this way, any tendency for the thread to fail to pass between the arms in the course of a rapid winding operation is minimized.

The tatting operation is carried out in the usual manner, with the shuttle being passed through the loop of thread which is formed on the fingers of the user. When the thread is to be passed through a picot, the pointed end 29 is inserted in the picot and engages the thread. The pointed end is then withdrawn and draws with it the thread which is then brought through the picot.

Although the invention has been described in connection with a specific embodiment, it will be apparent that modifications and changes may be made without departing from the spirit and scope of the invention.

I claim:

1. A tatting shuttle comprising a frame of substantially uniform thickness in cross section throughout providing a core for receiving and winding of thread, a pair of arms extending forwardly and toward each other from opposite ends of said core in adjacent opposed relation, a second pair of arms extending rearwardly and toward each other from opposite ends of said core in adjacent opposed relation, each of the adjacent opposed surfaces of said pairs of arms which extend inwardly toward said core from the end of the arm being inclined toward the adjacent opposed arm whereby the ends of each pair of arms provide a tapered thread-receiving groove of a maximum width at the end of the arms.

2. A tatting shuttle comprising a frame providing a core for receiving and winding of thread, a pair of arms extending forwardly and toward each other from opposite ends of said core in adjacent opposed relation, a second pair of arms extending rearwardly and toward each other from opposite ends of said core in adjacent opposed relation, the end portion of each of the adjacent opposed surfaces of each of said pairs of arms extending downwardly from the upper edge of the arm and extending upwardly from the lower edge of the arm, being inclined toward the adjacent opposed arm, whereby the upper and lower end portions of each pair of arms provide a tapered thread-receiving groove of a maximum width at the upper and lower surfaces respectively said arms being of substantially uniform thickness in cross section throughout.

3. A tatting shuttle as set forth in claim 1 wherein the end portion of each of the adjacent opposed surfaces of each of said pairs of arms extending downwardly from the upper edge of the arm and extending upwardly from the lower

edge of the arm is inclined toward the adjacent opposed arm whereby the upper and lower end portions of each pair of arms provide a tapered thread-receiving groove of a maximum width at the upper and lower surfaces respectively.

4. A tatting shuttle comprising a frame providing a core for receiving and winding of thread, a pair of arms extending forwardly and toward each other from opposite ends of said core in adjacent opposed relation, a second pair of arms extending rearwardly and toward each other from opposite ends of said core in adjacent opposed relation, each of the adjacent opposed surfaces of said pairs of arms which extend inwardly toward said core from the end of the arm being inclined toward the adjacent opposed arm whereby the ends of each pair of arms provide a tapered thread-receiving groove of a maximum width at the end of the arms, one of said arms having an elongated arcuate pointed end slightly curved back upon itself to form a hook and extending beyond the end of the adjacent opposed arm and adapted to be used in passing a thread through a picot.

5. A tatting shuttle as set forth in claim 1 wherein one of said arms is provided with an elongated arcuate pointed end slightly curved back upon itself to form a hook and extending beyond the end of the adjacent opposed arm and adapted to be used in passing a thread through a picot.

6. A tatting shuttle comprising a core portion of substantially uniform thickness in cross section, a pair of arms extending from said core section in each direction to provide flat members lying in the same plane with said core and providing a flared thread-receiving groove between the ends of the arms, at least one of said arms, which is inclined toward the other arm, being curved backward in a direction away from the other arm to provide a thread-receiving hook.

7. A tatting shuttle comprising a flat longitudinal body having a core portion of substantially uniform thickness in cross section, a pair of arms extending from said core section in each direction to provide flat members lying in the same plane with said core and providing a flared thread-receiving groove between the ends of the arms, at least one of the arms, which is inclined toward the other arm, being curved backward in a direction away from the other arm and terminating in a point to provide a thread-receiving hook.
